CABINET FOR A TELEVISION RECEIVER

Eugene Aeschliman, Cincinnati, Ohio, assignor to Avco Manufacturing Corporation, Cincinnati, Ohio, a corporation of Delaware

Application May 19, 1954, Serial No. 30,566

Term of patent 14 years

(Cl. D56—4)

Fig. 1

Fig. 2

Fig. 1 is a perspective view of a cabinet for a television receiver embodying my new design, showing the front, right side, and top thereof; and

Fig. 2 is a side elevational view of the television receiver cabinet shown in Fig. 1.

The back and left side of the cabinet are plain.

I claim:

The ornamental design for a cabinet for a television receiver, as shown and described.
